UNITED STATES PATENT OFFICE.

GEORG SPIESS, OF LEIPZIG, GERMANY.

CONTROLLING DEVICE FOR USE IN SHEET-FEEDING AND LIKE MACHINES.

1,160,208.

Specification of Letters Patent. Patented Nov. 16, 1915.

Application filed June 24, 1915. Serial No. 36,142.

To all whom it may concern:

Be it known that I, GEORG SPIESS, subject of the Emperor of Germany, and a resident of Leipzig, Saxony, Germany, have invented certain new and useful Improvements in or Relating to Controlling Devices for Use in Sheet-Feeding and like Machines, of which the following is a specification.

Where sheet feeding machines are employed, for instance, to supply a high-speed press having an automatic sheet registering mechanism it frequently happens that the feed of the individual sheets must be suddenly interrupted. In such a case it is desirable that the high speed press as well as certain moving parts of the sheet registering and sheet feeding mechanisms are not disturbed from and allowed to continue their regular motion. On the contrary, these devices should be capable of continuing their movement and of remaining ready for immediate use at their normal speed as soon as they are thrown into action.

The object of this invention is to prevent the injury to or breakage of such moving parts due to their sudden stoppage and the delay which must necessarily result if such parts, after being stopped, have first to attain their normal speed.

Now, this invention has for its object to control the chief moving parts in the sheet feeding mechanism, viz: the combing device and the roller supplying the bank of sheets to the same, so that the actual feeding operation of these parts may temporarily be stopped at will without preventing them from continuing the movement which they derive from the driving means.

To this end according to the present invention, the lever which serves in a known manner to automatically raise the combing wheels of the sheet feeding mechanism is connected to a manually operated device which is also employed to control the sheet feeding roller. By the actuation of the said device the operation of the combing wheels, the sheet feeding roller and the sheet brake are simultaneously interrupted for any desired period of time.

The invention is illustrated by way of example in the accompanying drawings, in which:

Figure 1 is a lateral elevation of the principal parts of a sheet feeding machine provided with the controlling device. Fig. 2 shows some of the parts indicated in Fig. 1

in the position which they assume during the action of the controlling device, certain other parts being omitted for the sake of clearness, and Fig. 3 is a top plan view of Fig. 1.

Secured to an operation shaft 2 is a hand lever 1. The same shaft also carries a cam 4 which serves to raise the combing wheel 3 by depressing an arm 5 arranged on the shaft 6 which as usual carries also the lever 8 which is adapted to coöperate with the carrier 7 of the combing wheel 3 in a well known manner. This carrier 7 is constructed in the form of a housing containing the driving gear for the combing wheel. Mounted on the shaft 2, moreover, is a toothed segment 9 meshing with a corresponding segment 10 on a shaft 11. Secured to the shaft 11 is an arc-shaped cam 12 so as to move with the segment 10 in which movement the cam 12 coöperates with a cam 13 which is rotatably arranged on the shaft 2. These two cams are adapted to lock the lever arm 5 in the position to which it has been depressed by the cam 4 as indicated in Fig. 2. The cam 13 also serves to control the operation of the driving mechanism for the sheet feeding roller 32.

When in the position shown in Fig. 2 the cam 13 bears, by means of its recessed rear end, against a pin 27 on a rocking arm 28 which, by means of a hub 15, is loosely rotatable on the shaft 2. By means of a connecting rod 34 the rocking arm 28 is connected in a well known manner to the rocking arm 35 which carries the ratchet pawl 36 actuating, by means of the usual ratchet wheel and through the agency of the toothed wheels 37 and 38, the sheet feeding roller 32 in an intermittent manner. The member for driving the mechanism shown in the present case is a crank disk 23 to the crank pin 30 of which is attached a connecting rod 29, the free end of which is provided with a slot embracing a pin 40 secured on the rocking arm 28. According to the position of the pin 40 within the slot in the connecting rod 29 the rocking arm 28 is moved by the connecting rod 29 to a greater or smaller extent and this movement is transmitted by the connecting rod 34 to the rocking lever 35 and, consequently, to the feeding roller 32. Now, by the cam 13 above referred to the rocking arm 28 may be moved to such a position as to prevent any movement from being imparted to it

- by the connecting rod 29 or only a movement so slight as to be insufficient for the pawl 36 to engage a new tooth of its ratchet wheel. In this case the usual spring 31 can 5 likewise no longer retract the connecting rod 34 and, accordingly, the ratchet gear cannot perform any feed action. While, however, by raising the combing wheel 3 with the aid of the hand lever 1 the feed of sheets 10 from the pile feeding roller by the combing device is interrupted a certain amount of feed would still be possible as the usual sheet brake 18 continues to perform its movement on the bank of sheets 26. In order to 15 prevent this also an arm 14 is secured to the shaft 2 and has its free end attached to a connecting rod 16, the other end of which is connected to the guide rails 17 which support the carriage 20 upon which the sheet 20 brake is mounted. The rails 17 are connected to two rocking levers 19 to which a swinging movement is imparted from a cam 22 by a connecting link 25, of which one end is guided on the cam by means of a roller 24. 25 By rotating the hand lever 1 into the position shown in Fig. 2 the rails 17 are raised by the arm 14 and, accordingly, the brake 18 is moved out of the path of the sheets while the transmission of movement thereto 30 from the cam 22 is interrupted by the roller 24 being thrown out of engagement therewith. Therefore, by one single movement of the hand lever 1 the combing wheel 3 is raised without impeding its rotary movement, the feed movement of the sheet supply roller 32 is interrupted and the sheet brake 18 is raised out of action.
- Having now particularly described and ascertained the nature of my said invention 35 and in what manner the same is to be performed, I declare that what I claim is:—
1. A controlling device for use in sheet feeding and like machines comprising a sheet supply roller, a sheet brake, the comb-

ing wheels, a hand operated lever controlling 45 the combing wheels, and cams actuated by the movement of said hand operated lever whereby the supply roller and the sheet brake are simultaneously interrupted when the combing wheels are raised from the 50 sheets.

2. A controlling device for use in sheet feeding and like machines comprising a sheet supply roller, a sheet brake with movable support, the combing device, a separate 55 shaft, a hand operated lever thereon controlling the combing device, a cam on said separate shaft for raising the combing wheel, a rocking arm transmitting movement to the said roller, a locking cam on the separate shaft for adjusting and locking said 60 rocking arm, and an arm actuating the sheet brake support so as to move the brake out of contact with the bank of sheets.

3. In a controlling device for use in sheet 65 feeding and like machines, a sheet feeding roller, a rocking arm transmitting movement to the roller, a controlling shaft, a toothed segment thereon, a second toothed segment meshing therewith, a cam actuated by the 70 second segment, and a locking cam on the controlling shaft coöperating with the cam actuated by the second segment.

4. In sheet feeding and like machines, a hand operated controlling device adapted to 75 temporarily interrupt the operation of the combing wheels, the sheet feeding roller and the sheet brake simultaneously comprising a separate shaft, a hand operated lever thereon, and means in connection therewith 80 for temporarily interrupting the operation of the active parts named.

Signed at Leipzig, Germany, this 4th day of May, 1915.

GEORG SPIESS.
